UNITED STATES PATENT OFFICE.

OSCAR C. SCHMIDT, OF CINCINNATI, OHIO, ASSIGNOR TO THE CINCINNATI BUTCHERS' SUPPLY COMPANY, OF CINCINNATI, OHIO, A CORPORATION OF OHIO.

COOLING APPARATUS FOR CONGEALABLE SUBSTANCES.

Application filed July 12, 1924. Serial No. 725,636.

My invention relates to cooling apparatus for congealable substances, and is applicable for instance for congealing melted lard, although it may be used for other purposes.

5 In employing my improved device in hardening or congealing lard, the melted lard, received from the rendering apparatus, is fed against the outer periphery of the roll or cylinder, which is rotated, and is arranged to cool the lard, the cooled lard being discharged from the roll.

In structures of this character now in general use, ammonia is used as a refrigerating agent, the ammonia being received directly 15 into the body of the roll or cylinder and discharged therefrom, expanding throughout the body of the roll for cooling the roll. A safety valve is usually employed to guard against too high a pressure in the roll, but 20 on account of neglect of operators in testing the safety valve with sufficient frequency, explosions of rolls have taken place, resulting in injury and destruction to persons and property.

25 I avoid these objections in my improved device, in which I employ cooling piping in the roll, and surround the piping with a temperature-transmitting fluid, for transmitting the cooling effect from the piping to the wall 30 of the roll, and I further so arrange the piping as to avoid air pockets therein, which would result in hammering and noises in the piping, and would be detrimental to the uniform passage of the cooling agency through 35 the piping.

I prefer to arrange the piping with an inlet and with an outlet which are coincident with the axis of rotation of the roll, and to arrange the piping in the roll so as to be maintained below the upper portions of 40 the axial passage for the cooling agent passing through the trunnions of the roll, and preferably formed in loops arranged in tiers one above the other; so that the expanding 45 gases rise from tier to tier and are discharged in such a manner as to avoid the formation of air-pockets in the piping.

It is the object of my invention, further, 50 to provide cooling piping inside the roll, formed in loops extending lengthwise of the roll, and arranged so that the change of ele-

vation in the piping from its lowermost point in the roll is a continuous rise from elevation to elevation until discharged from the roll.

It is the object of my invention, further, to provide a roll of the character mentioned with trunnions at its ends, journaled in bearings, and piping in the roll having extensions at the outer ends of said bearings, and supplemental bearings beyond the ends of said first-named bearings arranged to support said pipe-extensions; and, further, to provide a roll of the character mentioned with trunnions, and stationary bushings in 60 the trunnions having inlet and outlet passages for a refrigerating gas therethrough and supporting cooling pipes at their inner ends inside the roll.

The invention will be further readily 70 understood from the following description and claims, and from the drawings, in which latter:

Fig. 1 is a front elevation of my improved device.

Fig. 2 is an end elevation of the same.

Fig. 3 is a cross-section of the same, taken on the irregular line 3—3 of Fig. 1, partly broken away.

Fig. 4 is a detail taken in section on the 80 line 4—4 of Fig. 3.

Fig. 5 is a vertical longitudinal section of my improved device, taken on the line 5—5 of Fig. 2, partly broken away.

Fig. 6 is a cross-section, taken on the line 85 6—6 of Fig. 5.

Fig. 7 is a detail in section, taken on the line 7—7 of Fig. 8.

Fig. 8 is a plan view of my improved device, with the roll and parts in connection 90 therewith partly in section in the plane of the line 8—8 of Fig. 3.

Fig. 9 is a horizontal section of the roll and the piping therein, taken in the plane of the line 9—9 of Fig. 3.

Fig. 10 is a similar view, taken in the plane of the line 10—10 of Fig. 3; and,

Fig. 11 is a similar view, taken in the plane of the line 11—11 of Fig. 3.

21 represents a roll, exemplified as having 100 a lengthwise inclosing wall 22, shown in the form of a cylinder, and heads 23, 24, the

ends of the wall 22 being received in annular rabbets 25 in the heads, the parts being clamped together for forming a tight joint between the walls by means of tie-rods 26 and nuts 27.

The heads are provided with trunnions 31, 32, journaled in bearings 33, 34, on end-frames 35, 36, secured together by means of tie-rods 37. Bushings 41, 42, extend through 10 the respective trunnions. These bushings extend outwardly beyond the trunnions, and are respectively supported in supplemental bearings 43, 44. The bearing 43 is fixed on a floor-stand 45, and having a bracket 46 15 thereon, on which an electric motor 47 is fixed. A set-screw 48 fixes the bushing in said bearing.

The bearing 44 is fixed to brackets 51, shown in the form of channel-irons, fixed by 20 bolts 52 to the upper ends of the bearing 34, the supplemental bearing 44 being fixed to the outer ends of said brackets by bolts 53. A set-screw 54 fixes the bushing 42 to the bearing 44.

25 The inner ends of the bushings are provided with heads 55, 56, from which pipe-racks 57, 58, are suspended, being shown fixed thereto by bolts 59. Each of these pipe-racks consists of an upper cross-piece 30 61, secured to the bushing, and depending hanger-strips 62, which converge toward their lower ends, and are fixed to said upper cross-piece. Cross supporting strips 63, 64, 65, are fixed to said depending strips.

35 Piping is provided for the inside of the roll, and is exemplified as formed in loops 71, extending lengthwise of the roll, the loops being arranged in series 72, 73, 74 and 75, preferably arranged in tiers one above 40 the other. The piping has extensions 77, 78, at its respective ends, forming passages through the bushings, valves 79, 80, being located at the outer ends of said extensions for controlling the passage of the cooling gas 45 through the piping. The valve 79 is a pressure-reducing valve for controlling the expansion of the gas admitted into the piping, and the valve 80 is a pressure-controlling valve for aiding in controlling the expansion 50 of gas in the piping.

The cooling agent which I prefer to employ is ammonia, which is compressed to substantially liquid state and at a pressure of approximately 180 pounds per square 55 inch at the outer end of the valve 79, which is preferably regulated so that the gas in the piping located in the roll expands in the piping to a reduced pressure of approximately 18 pounds per square inch, as an 60 example.

The gas is drawn from the piping through the valve 80, in the practical operation of the device, by means of a suitable compressor, which compresses the ammonia gas 65 to its highly compressed or liquid state,

drawing the gas through the valve 80, so as to permit expansion of the gas in the piping in the roll for causing cooling by said piping. It is to be understood that the outlet-pipe may communicate with the outlet piping of a series of other rolls or with other cooling coils. It will be also understood that other cooling gases and different pressures 70 may be employed.

The piping in the roll is surrounded by a body 81, of cooling fluid, as indicated in Fig. 3, which may for instance be brine, preferably a salt-brine of high salt content, registering for instance one hundred degrees on a pickle scale or salometer.

The roll is preferably filled with such cooling liquid, through which heat is transmitted from the wall of the hollow roll to the piping, heat in said wall being transmitted to said liquid, and heat of said liquid 85 being transmitted to said piping. The cooling liquid is received into and discharged from the roll through holes 82, each normally closed by a plug 83 threaded into said hole.

90 There is preferably a compressible packing 85 between the outer end of each of the trunnions and its bushing, comprising, for instance, a gasket 86 and a gland 87 received in an annular rabbet 88 in the trunnion about the bushing, the gland being adjustable by suitable nuts 89 received over bolts 90.

95 A compressible packing 91 is located between the outer end of each of the bushings and the extension of the pipe therein, and may comprise a gasket 92 and a gland 93 received in an annular rabbet 94 between the bushing and the extension of the pipe, the gland being threaded in the wall of said rabbet for adjustment.

100 The packings 85 prevent escape of fluid through the joint between the rotating trunnion and the stationary bushing, and the packings 91 prevent escape of gas through the joint between the pipe and the bushing.

110 The trunnion 31 has a gear 97 fixed thereto. This gear is meshed with a pinion 98 fixed to the armature shaft of the motor.

115 The inlet extension of the pipe is received through the bushing 41. The piping in the roll at its inlet end is preferably provided with an abrupt bend 101 from which a descending portion 102 of the piping extends 120 preferably directly to the lower length 75 of the loops of piping in the roll, connecting therewith by an abrupt bend 103.

125 The other end of said lowermost stretch of piping is connected with the second series of loops by an ascending branch 105 connecting with a side stretch of the second series of loops, the gas rising therethrough from the lowermost series to the second series of loops. The other end of said second series of loops is connected with the third 130

series of loops by an ascending branch 106, connecting with an outer stretch of said third series of loops.

The third series of loops is connected with 5 the upper series of loops by means of an ascending branch 107 connecting with an outer stretch of said upper series of loops. The other end of said upper series of loops is provided with a lateral branch 108 provided with a bend 109 to connect with the outlet extension 78 of the pipe.

The number of series of piping may be varied, depending largely on the diameter of the cooling roll, a larger diameter of cooling 15 roll being preferably provided with a greater number of series of loops. I have shown a preferred arrangement of loops. Other arrangements of piping may be employed without departing from the spirit of 20 my invention expressed in the appended claims.

The ends of the loops are supported by the cross-pieces 63, 64, 65, supported by the bushings at the respective ends of the drum 25 and the hangers to which they are secured, forming racks for supporting the piping.

Intermediate racks 111, 112, may also be provided for aiding in supporting the piping and maintaining the same in level relation. Said intermediate racks may comprise 30 an upper cross-piece 113 and supporting cross-pieces 114, 115, 116, and hangers 117 to which the cross-pieces are rigidly secured.

The piping in the roll is preferably so 35 arranged that the incoming gas is at once directed to the lowermost point in the piping, and from said lowermost point gas is permitted to move horizontally or upwardly to its outlet, whereby air-pockets in the piping are avoided, and continuous travel and expansion of the gas is assured.

The substance operated on, for instance 45 lard, may be received from the rendering apparatus through a pipe 121, having branches 122, on which there are nozzles 123, provided with valves 124, for discharging into a trough 125, extending lengthwise of the roll. The trough comprises a trough-section 126, which comprises a bottom, an 50 outer wall, and end walls, and is supported by brackets 127 on the end-frames of the machine. The brackets are rigidly secured to the end-frames, and have guide-ways 128, in which the trough-section is slidable. The 55 outer wall of the roll forms the inner wall of the trough. The trough-section is urged toward the roll by means of springs 131, received about rods 132, fixed to lugs 133, extending from the respective brackets.

60 The rods are received through lugs 134 formed on the ends of the trough-section, the springs being located between said lugs and nuts 135 threaded over the outer threaded ends of said rods. Adjustment of the 65 nuts forces the trough-section with greater

or less pressure toward the periphery of the roll. There may be a cushion-lining 137 dovetailed into the inner edges of the trough-section for cushioning said inner edges against the roll and preventing leakage of material between the trough-section and the roll.

70 A scraper-blade 141 extends lengthwise of the roll, and is preferably supported on the lower wall of the trough-section, the scraper-blade being preferably a flexible blade, fixed to a bar 142 extending lengthwise of the bottom of the trough-section, and held slidably thereto by means of screws 143, threaded into the bottom of the trough-section 75 through slots 144 in said bar. Adjusting screws 145 are threaded into an apron 146 depending from the trough-section, and abut the bars 142 for urging the scraper-blade 80 toward the outer periphery of the roll. 85

Molten material, for instance hot lard, is fed into the trough. The roll rotates in the direction of the arrow *a*, and carries with it adhering material from the trough. The peripheral wall of the roll being cooled, 90 causes congealing of the material upon the same as it is carried about with the roll, the congealing continuing until the scraper-blade is reached, which latter acts to scrape the congealed material from the roll. The 95 material thus scraped from the roll may be received into a trough 148, from which it is removed by suitable conveyor or other mechanism.

100 By means of my improved device regular absorption of heat from the wall of the roll to the piping is maintained for cooling said wall, and the temperature of the outer periphery of the roll is readily regulated to provide proper cooling surface for the congealable substance, for instance lard, operated on, according to the speed with which the substance operated on is fed to the roll and the speed of rotation of the roll.

105 The apparatus is simple and safe, and effective for congealing the material, and for feeding the hot material and gathering the cooled material. Danger from explosion of the roll is avoided, for the reason that the gas expands in the pipe only, which is capable of withstanding a greater pressure than the roll, and if a rupture in the piping should take place, it is cushioned by the cooling liquid in the roll and danger therefrom is avoided.

110 Having thus fully described my invention, what I claim as new, and desire to secure by Letters Patent, is:

1. In a cooling apparatus for congealable substances, the combination of a hollow roll, cooling piping formed into substantially horizontal loops in said roll and having an inlet into said roll and an outlet from said roll, said outlet being substantially as high as said inlet and said loops in said 115 120 125 130

roll, whereby to resist the formation of air-pockets in said piping, said roll arranged for receiving a cooling fluid therein about said piping whereby to abstract heat from the outer wall of said roll by said piping, means for feeding the substance to be operated on in liquid form against the outer periphery of said roll, and means for removing said substance from said outer periphery.

2. In cooling apparatus for congealable substances, the combination of a hollow roll, means for rotating the same, cooling piping in said roll having an inlet-extension and an outlet-extension, said extensions being substantially coincident with the axis of rotation of said roll, said piping between said inlet-extension and said outlet-extension being arranged in substantially horizontal loops, said loops located solely within the middle portion and the lower portion of said roll, and constructed and arranged for receiving a body of cooling fluid between said piping and the outer wall of said roll for abstracting heat from said wall by said body of cooling fluid and abstracting heat from the latter by said piping, means for feeding the substance to be congealed in liquid form against the outer periphery of said roll, and means for removing said substance in congealed form from said outer periphery.

3. In congelation apparatus, the combination of a hollow roll having an outer periphery on which the cooling takes place, means for rotating said roll, cooling piping in said roll, means for supporting said piping non-rotatively in said roll comprising a bushing and an extension of said piping in said bushing, said roll comprising a trunnion in which said bushing is located, means for securing said bushing against rotation, packing between said trunnion and said bushing, packing between said bushing and said piping, a body of liquid in said roll surrounding said piping to abstract heat from the wall of said roll by said body of liquid and to abstract heat from said body of liquid by said piping, said piping being imperforate in said roll, and constructed and arranged whereby said body of liquid forms a cushion for explosive pressure from said piping upon rupture of said piping in said roll, and feeding means and take-off means for the outer periphery of said roll.

4. In congelation apparatus, the combination of a hollow roll having an outer periphery on which the cooling takes place, means for rotating said roll, cooling piping in said roll, means for supporting said piping non-rotatively in said roll, a body of brine liquid in said roll surrounding said piping to abstract heat from the wall of said roll by said body of liquid and to abstract heat from said body of liquid by said piping, said piping formed in loops extending lengthwise of

said roll and arranged in superposed series continuously feeding from a lower series to a series thereabove, and feeding means and take-off means for the outer periphery of said roll.

5. In a cooling apparatus for congealable substances, the combination of a hollow roll, cooling piping in said roll consisting of reversely arranged lengths of pipe extending lengthwise of the roll and arranged in series one above another with each lower series feeding into a series thereabove, said cooling piping provided with an infeeding section having connection with said lower series and with an out-feeding section having connection with said upper series, said sections being substantially coincident with the axis of rotation of said roll, and constructed and arranged for receiving a body of cooling liquid in said roll about said piping for abstracting heat from said roll by said cooling liquid and abstracting heat from said cooling liquid by said piping, means for feeding the substance to be congealed in liquid form against the outer periphery of said roll, and means for removing said substance in cooled state from said outer periphery.

6. In a cooling apparatus for congealable substances, the combination of a rotatable hollow roll, said roll having journal extensions at its respective ends, bearings at the ends of said roll for said journal extensions, stationary bushings in said bearings, cooling piping in said roll, and pipe racks stationarily supported by said stationary bushings, said cooling piping supported by said pipe racks, and said cooling piping comprising end extensions in said stationary bushings.

7. In a cooling apparatus for congealable substances, the combination of a rotatable hollow roll, said roll having journal extensions at its respective ends, bearings at the ends of said roll for said journal extensions, stationary bushings in said bearings, cooling piping in said roll supported by said bushings, said cooling piping having end-extensions in said bushings, supplemental outer bearings for said bushings, stationary supports for the latter, compressible packings between said end-extensions and the outer ends of said bushings, and compressible packings between said first-named bearings and said bushings located between said first-named bearings and said second-named bearings.

8. In a cooling apparatus for congealable substances, the combination of a substantially horizontal hollow roll provided with end-trunnions on which the same is rotated, cooling piping arranged in loops in said roll, said loops extending lengthwise of said roll and arranged in superposed series in said roll, said piping including an inlet and an outlet at opposite ends of said roll substan-

- tially coincident with the axis of rotation of said roll, said inlet having connection with the lowest of said series by means of a substantially direct downward passage connection, each lower series having passage connection with a series thereabove, the upper series having passage connection with said outlet, said roll arranged for receiving a body of cooling liquid surrounding said piping in said roll for abstracting heat from the wall of said roll by said body of liquid and abstracting heat from said body of liquid by said piping, means for feeding the substance to be cooled in liquid form against the outer periphery of said roll, and means for removing the cooled substance from said outer periphery.
9. In a cooling apparatus for congealable substances, the combination of a substantially horizontal hollow roll provided with end-trunnions on which the same is rotated, cooling piping arranged in loops in said roll, said loops extending lengthwise of said roll and arranged in superposed series in said roll, said piping including an inlet and an outlet at opposite ends of said roll substantially coincident with the axis of rotation of said roll, said inlet having connection with the lowest of said series by means of a substantially abrupt downward passage connection, each lower series having passage connection with a series thereabove, the upper series having passage connection with said outlet, said piping located wholly below the horizontal plane of the upper portions of said trunnions, said roll arranged for receiving a body of cooling liquid surrounding said piping in said roll for abstracting heat from the wall of said roll by said body of liquid and abstracting heat from said body of liquid by said piping, means for feeding the substance to be cooled in liquid form against the outer periphery of said roll, and means for removing the cooled substance from said outer periphery.
10. In a cooling apparatus of the character described, the combination of a hollow roll, trunnions at the ends of said roll, bearings therefor, stationary bushings in said trunnions, cooling piping in said roll supported by said bushings, said cooling piping having end-extensions in said bushings, supplemental outer bearings for said bushings, stationary supports for the latter, and valves at the outer ends of said respective end-extensions, said supplemental outer bearings located between said valves and said first-named bearings.
11. In a cooling apparatus of the character described, the combination of a substantially horizontal hollow roll, means for rotating the same, piping in said roll having an inlet-extension and an outlet-extension, said extensions being substantially coincident with the axis of rotation of said roll, said piping between said extensions arranged in substantially horizontal loops extending lengthwise of said roll, said loops arranged in superposed substantially horizontal series, the lowest loop of said horizontal loops having connection with said inlet-extension and each lower series having connection with the series thereabove, the upper series having connection with said outlet-extension, said roll arranged for receiving a body of cooling liquid surrounding said piping, said roll provided with openings for charging said liquid into and discharging the same out of said roll, and control means for said openings.
12. In a cooling apparatus of the character described, the combination of a frame, a substantially horizontal hollow roll, trunnions therefor, bearings for the latter on said frame, bushings in said trunnions, piping in said roll, said piping having end-extensions in said bushings, outer supports for said bushings spaced endwise from said first-named bearings, a floor-stand supporting one of said outer supports, a bracket extending from said frame supporting the other of said outer supports, and driving means for rotating said roll located between said floor-stand and said frame.
- In testimony whereof, I have hereunto signed my name.

OSCAR C. SCHMIDT.
